UNITED STATES PATENT OFFICE.

KENNETH J. VAN SICKLE AND FREDERICK G. TRULAN, OF SENECA FALLS, NEW YORK.

CAMERA.

1,144,267.

Specification of Letters Patent. Patented June 22, 1915.

Application filed June 30, 1914. Serial No. 848,255.

To all whom it may concern:

Be it known that we, KENNETH J. VAN SICKLE and FREDERICK G. TRULAN, citizens of the United States, residing at Seneca Falls, in the county of Seneca and State of New York, have invented certain new and useful Improvements in Cameras; and we do hereby declare the following to be a full, clear, and exact description of the invention, such as will enable others skilled in the art to which it appertains to make and use the same.

This invention relates to cameras, and has for its object to provide a device of this character constructed in the shape of the improved automatic pistol and the shutter of which is operable by a trigger, whereby the camera may be conveniently and accurately focused upon the object or person to be photographed.

With these and other objects in view, the invention consists in the novel construction, arrangement and formation of parts as will be hereinafter specifically described, claimed and illustrated in the accompanying drawings, in which:

Figure 1 represents a longitudinal sectional view through the camera. Fig. 2 represents a side elevation thereof on a reduced scale. Fig. 3 represents a side elevation, partly broken away, of the film-receiving and winding cage. Fig. 4 represents a transverse sectional view on the line 4—4 of Fig. 1.

Referring to the drawings in detail, wherein similar reference numerals designate corresponding parts throughout the several views, the numeral 5 indicates generally the casing of the camera which is preferably constructed in the usual shape of an automatic pistol and comprises a handle portion 6 and barrel portion 7 extending angularly from the upper end of the handle 6 and formed integral therewith. A trigger guard 8 is secured between the barrel 7 and handle 6 and a trigger 9 is pivotally secured at 10 in the guard 8. The front end wall of the handle portion 6 is extended forwardly within the barrel portion 7 and in spaced relation to the lower portion of the latter. The forwardly extending portion of the front wall of the handle 6, designated by the numeral 11, connects with a transversely extending partition 12 secured within the barrel and providing, in conjunction with the wall 11, a dark chamber 13. The por-

tion of the barrel 7 adjacent the handle 6 is cut away to provide a longitudinal opening 14 in which the free end of the trigger 9 operates. The front end 15 of the barrel is provided with an opening 16 for admitting light through the opening 17 and lens 18 in the partition 12, when the shutter 19 is opened. A wire, or the like, 20 is secured at one end in the forward end of the barrel 7 and is secured at its rear end to the free extremity of the trigger 9. A spring 21 is secured adjacent the front end of the wire 20 and connects with the shutter 19 for operating the latter when the wire 20 is drawn taut or straight by the trigger 9.

The end wall 22 of the handle 6 is removable and carries a pair of spaced plates 23 constituting a cage or holder for the film. A pair of spaced rollers 24 is rotatably mounted in the plates 23 adjacent the lower end and rear edge of the latter and is adapted to guide a roll of films passing thereover in proximity to the opening 25 formed in the handle portion 6 and suitably covered with a semi-transparent material, whereby the numbers arranged in spaced relation on the film backing are visible. A second pair of rollers 26 is rotatably mounted between the plates 23 adjacent their upper ends and forward edges for guiding the film in position for exposure to the rays of light admitted through the lens 18, when the shutter 19 is operated. The roll of unexposed film is wound on the usual spool 27 and rotatably mounted between the side plates 23 adjacent their lower ends, and the film 28 is extended upwardly between said plates and positioned over the pairs of rollers 24 and 26 in the manner illustrated in Fig. 1. A spool 29 on which the exposed film is wound is rotatably mounted between the plates 23 adjacent their upper ends, and the spool 29 is rotated to wind the film, subsequently to an exposure thereof, by a key 30 rotatably mounted in one of the side walls of the handle portion 6 and carrying a shank 31 adapted to be moved inwardly to engage within a suitable opening in the spool 29 to lock the latter with said key for rotation.

The spool 29 is prevented from rotating in a direction to unwind the film by ratchet teeth 32 formed on one end thereof and co-operating with a spring pawl 33 secured to one of the plates 23 of the holder. An arm 34 of the spring 33 is extended between the plates and engaged against the film

coiled on the spool 29 for insuring proper winding of the film thereon.

What we claim is:

1. A camera including a hollow handle and a barrel communicating therewith, a film holder in said hollow handle, a trigger guard secured between said barrel and said handle, a trigger pivotally secured to said guard, a lens in said barrel, a shutter operably mounted in front of said lens, and operating connections between the free extremity of said trigger and said shutter for operating the latter.
2. A camera including a hollow handle and a barrel communicating therewith, a film holder in said hollow handle, a trigger guard secured between said barrel and said handle, a trigger pivoted to said trigger guard, a lens in said barrel, a shutter operably mounted in front of said lens, a wire secured at one end in said barrel and at the opposite end to the free extremity of said trigger, and an operating connection between said wire and said shutter.
3. A camera including a hollow handle and a barrel communicating therewith, a film holder in said hollow handle, a trigger guard secured between said barrel and said handle, a trigger pivotally secured to said

guard, a lens in said barrel, a shutter operably mounted in front of said lens, a flexible wire secured at one end in said barrel and at the opposite end to the free extremity of said trigger, and a spring connecting said wire intermediate its ends with said shutter.

4. A camera including a hollow handle and a barrel communicating therewith and having a longitudinal opening in its lower wall, an apertured partition disposed transversely within said barrel, the front wall of said handle being extended a distance within said barrel and connecting with said apertured partition, a trigger guard secured between said barrel and said handle, a trigger pivotally secured to said guard and projecting into said longitudinal opening, a lens in said apertured partition, a shutter operably mounted in front of said lens, and operating connections between the free extremity of said trigger and said shutter for operating the latter.

In testimony whereof we affix our signatures in presence of two witnesses:

KENNETH J. VAN SICKLE.
FREDERICK G. TRULAN.
